(57) **CLAIM**

I claim the ornamental design for a credit/debit card-receiving dispensing device, as shown and described.

DESCRIPTION

FIG. 1 is a perspective view of a credit/debit card-receiving dispensing device showing my new design;

FIG. 2 is a left side elevational view thereof;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a right side elevational view thereof.

The broken lines in the various FIGURES depict environmental structure for illustrative purposes only and form no part of the claimed design.
